SAFETY LOCK

Alois Crepinsek, Buenos Aires, Argentina

Application July 12, 1955, Serial No. 521,568

Claims priority, application Brazil July 13, 1954

8 Claims. (Cl. 70—153)

The invention relates to a safety lock comprising a latch-bolt guided in a lock-casing, a non-rotatable, axially movable hollow latch-pin traversing said latch-bolt for moving the latter from its locking position, and projecting on both sides of said lock casing with outer projecting parts and handles on its outer ends, one of which rotatably mounted, a locking member for the latch bolt in the latch-pin, rotatable internal control element for said locking members. Known safety locks of this kind are disadvantageous since there is no way of preventing the same, when in locked condition, from being unlocked by key means from outside of the door. For such purposes further bolts, which may only be served from the inner side of the door, or other further safety means are necessary.

An object of the invention is, to avoid these deficiencies and to improve the known safety locks by simple means.

According to the invention in such a safety lock a locking member for the rotatable internal control element is axially movably disposed in at least one of said handles, transverse slits are provided in one end of the hollow latch-pin and in the adjacent end of said rotatable internal control element opposite said axially movable locking member in the handle and cooperating therewith for securing said rotatable internal control element against rotation when said locking member is advanced in an axial direction and extends into said transverse slits. Within the rotatable handle an elastic supporting means is disposed, adapted to yieldingly hold said locking member in its releasing position and a movable driving means for said locking member is mounted to extend outside of said handle adapted to move said locking member in its locking position with respect to said rotatable internal control element.

Other particularities of the invention are hereinafter described and illustrated in the accompanying drawings in which

Fig. 1 is a horizontal middle section of a type of the safety lock with the axially movable latch pin,

Fig. 2 is a vertical section of the inner turning-button of the same safety lock with the corresponding parts,

Fig. 3 is a horizontal middle section of the same parts of the turning-button with the locking means for the rotatable internal control element in locking position,

Figs. 4 and 5 are lengthwise middle-sections of another type of the inner turning button with a locking member for the rotatable internal control element, and driving means for the locking member in locking position and releasing position actuated by a push-button,

Fig. 6 is a lengthwise middle-section of the same parts as in Figs. 4 and 5 during the changement of the locking member from releasing position to the locking position, when the push-button is pushed,

Fig. 7 is a lengthwise middle-section of the same parts as in Figs. 4 and 5 during the changement of the locking member from locking position to releasing position when the push-button is pushed,

Figs. 8 and 9 are lengthwise middle-sections of another

2

type of the push-button driving means for a locking member of the rotatable internal control element in two rectangularly intersecting planes in the releasing position of the locking member,

Fig. 10 is a lengthwise middle-section of the same parts of the push-button driving means as in Fig. 8 in locking position of the locking member,

Fig. 11 is a side view of the same locking member with holding means in the locking position,

Fig. 12 shows the same locking member with the movably and swivelly provided holding means during changement from the holding position to the releasing position,

Figs. 13, 14 and 15 are perspective representations of the hooked holding means for the locking member with its sidely arranged nose in releasing position, holding position and during the changement from the holding position to the releasing position.

In Fig. 1, 1 is the spring-catch formed as a longitudinally movable bolt, situated in the lock casing 2, and 20 yieldably held in locking position by spring 4, bearing against a transverse part 3 of the lock-casing 2. In the interior of the lock-casing 2 the bolt 1 has a hollow body, having behind the transverse part 3 a rectangular transverse channel 5 for the partly rectangular or square latch-pin 6, on the ends of which, extending on both sides from the casing 2, for example, the button-formed handles 7 and 8 are provided. The lock-casing 2 will be disposed in the door 9 in the manner of a mortise lock, so that the latch-pin 6 with the handles 7, 8 on 30 both sides of the door project from the sides of the door, the handle 7 being on the inside of the door.

The handle 7, disposed on the inner end of the latch-pin 6 and formed as a turning button, is located on the cylindrical end-part of the latch-pin 6 by a hollow cylindrical part 12 and fixed by a radial screw 10, so as to be 35 axially immovable with respect to the latch-pin 6, but turnable through only a predetermined angle on the latch-pin. For this purpose the connecting screw 10 is guided in a transverse slit 11 of the latch-pin, which 40 extends over an angle of about 180°. At the same time the connecting screw 10 grips in a radial hole of a rotatable internal control element 26, and therefore the inner turn-button 7 and the rotatable internal control element 26 are in mutual interconnection with each other. The hollow cylindrical part 12 of the turning button 7 is 45 guided in a hollow cylindrical sleeve 13 of the inner covering plate 14.

The turn button formed handle 8 at the outside of the door 9 is rigidly connected by a square section and a screw 15 with the square-formed latch-pin 6, and is 50 guided, with its hollow cylindrical part 16, in the hollow cylindrical sleeve 17 of the outer covering plate 18. The covering plates 14 and 18 are connected with each other in the correct position by means of threaded bushings 19, 20 fixed to the outer covering plate 18 and connecting screws 21, guided through the inner covering plate 14.

Between the guiding sleeves 13 and 17 of the covering plates 14 and 18 and the hollow cylindrical parts 12 and 16 of the handles 7 and 8 are provided at the inner side of the sleeves 13 and 17 and near the ends, guiding- and 60 packing-rings or sleeves 22 of caoutchouc or plastic materials. The handles 7, 8 carry on their outer ends end-buttons 23, with ring-formed holes 24, open to the door side and parallel to the hollow cylindrical parts 12 and 16, for receiving the guiding sleeves 13 and 17, if the 65 handles 7, 8 are moved axially with the latch-pin 6 toward the door.

In a longitudinal central cylindrical channel 25 of the latch-pin 6, the rotatable internal control element 26 is disposed axially immovable, but rotatable through a predetermined angle, and interconnected in the middle part of its length with a transversely movable locking-member

27, guided in the latch-pin 6 in such a way, that the locking member 27 is moved out of or into the latch-pin 6 when the internal control element 26 is rotated.

In the latch-bolt 1 is provided in opposite position to said locking member 27 a corresponding slit 28, in which the locking-member 27 engages to lock the bolt 1 in its outer locking position and at the same time to lock the latch pin 6 against axial movement. The locking member 27 and the corresponding slit 28 in the bolt 1 may be formed round, oval or rectangular in transverse direction.

The handle 8 on the outer side of the door with its button 23 is provided coaxially with the latch-pin 6 with a cylinder-lock 29, which is secured against axial movement, but which moves a coupling-member 30, which is disposed therein to couple the cylinder lock with the rotatable internal control element 26, in axial direction, if it is turned by a key for moving this coupling member 30 into a transverse end-slit 31 of the rotatable internal control element 26 and making a joint between the rotatable part of the cylinder lock 29 and the rotatable internal control element 26. Hereby the rotatable internal control element 26, after its coupling with the cylinder-lock, is rotated by the key of the lock so, that the locking-member 27 is moved into locking-position or out of this position to the releasing position for the bolt 1 and the latch-pin 6.

For moving the latch-bolt 1 from its locking position to the releasing position by means of axial movement of the latch-pin 6 there are disposed on opposite sides of the latter one or more angle-formed bars 33, which interact with abutments 34 in form of pegs or rolls on the latch-bolt 1. If the latch-pin 6 is axially moved, the angle formed bars 33 push against the abutments 34 on the latch-bolt 1 and remove the latter into the locking-casing.

In the hollow-cylindrical part 12 of the inner handle 7 formed as a turn-button according to the invention a hollow cylindrical space 35 is provided coaxial with the latch-pin 6 in which space is disposed an axially immovable, but rotatable driving-means 36 with an inclined inner area 37 and an outer-handle-piece 38 for a locking-member 39 with an inclined end-area 40, an axially guided, non-turnable locking-piece 41 and a spring 42. The locking-piece 41 is guided in a slit 69 of the intermediate wall 43 in the cylindrical space 35 of the hollow-cylindrical part 12 and extends axially into an end-slit 44 of the rotatable internal control element 26 and into an adjacent end-slit 45 of the non-turnable disposed latch-pin 6, to inhibit in this locking position, as shown in Fig. 3, any rotation of the rotatable internal control element 26. In this locking position it is impossible to rotate the rotatable internal control element 26, either by rotating the inner turn-button 7 or by rotating of the cylinder-lock 29 in the outer turn-button 8.

If now this internal control element 26 is in the position in which the locking-member 27 is introduced into the slit 28 of the bolt 1 with the key of the cylinder-lock it is impossible to open the safety lock by the key of the cylinder-lock 29 in the outer turn-button 8 and to remove the bolt 1 into the releasing position by axially movement of the latch-pin, which is locked too. The latch-bolt 1 can be removed by axial displacement of the latch-pin in its releasing position only after turning of the driving means 36 at the inner turn-button 7, until the inclined areas 37 and 40 are parallel to each other in juxtaposed position, in which position the locking piece 41 of the locking member 39 is removed from the slits 44 and 45 of the latch-pin 6 and the internal control element 26.

In Figs. 4 to 6 at the inner-turning-button 7 a push-button 74 with corresponding transmitting-members is provided, serving as driving-means for the locking member 72. At the locking member 72 there is movably disposed a locking lever 47 with a laterally extending nose 48 at one end, and an abutment 49 at the other end, and

a movable member 50 transversely guided on the locking member 72. This movable member 50 has control areas, inclined to each other and provided with oppositely positioned end abutments 51, 52, for a laterally movable or elastic transmitting plate-like member 53 fixed with one end to the push-button and cooperating with its lower free end with the abutments 51, 52, and the control areas of the movable member 50 for displacing the latter. The push-button 74 is supported upon said movable member 50 by a helical spring 54. For the laterally extending nose 48 of the locking-lever 47 a slit 55 is provided in the wall of the hollow-cylindrical part 12. The locking-lever 47 is held elastically in the locking position by a spring 56. A lengthwise slit 57 in the locking member 72 and a pin 58 fixed in the wall of the hollow-cylindrical part 12 and transversing the slit 57, limit the axial movement of the locking member 72 and prevent rotating of the latter. The plate-like movable member 50 may be guided in a corresponding straight-lined or arc-shaped 20 guide on the locking member 72 transversely to the moving direction of the latter. It is yieldingly held in its end-positions by one or more stops or arresting means 59 in or near these end-positions in such a manner that it rests in the respective position for releasing or locking 25 the locking-member 72, until the push-button 74 is pushed down again. In this manner the movable member 50 is moved, by successive pushing down of the push-button 74, alternately to the right and to the left, and the locking member 72 is moved alternately into the locking-position 30 and into the releasing position for the rotatable internal control element 26.

In the type of push-button driving means for the locking member of the rotatable internal control element 26 according to Figs. 8 to 10, there is provided a plate-like locking member 70 corresponding with the locking member 41 in Figs. 1 to 3 with one end rigidly fixed at the push-button 75 being secured against rotating by guiding in the slit 69 of a separating wall 71 in the hollow space 35 of the hollow-cylindrical part 12 and fixed to 35 the end of the hollow latch-pin 6. A lateral abutment 60 overhanging at one side of the plate-formed locking member 70 cooperates with a hook-shaped holding-piece 61, being pivotally mounted at the hollow latch-pin 6. The push-button 75 is supported by a helical spring 54, 40 which rests upon the separating wall 71. The hook-shaped holding piece 61 has an arc-shaped and downwardly inclined transverse part 62, at which an arc-shaped or downwardly inclined plate 63 is mounted. The hook-shaped holding piece 61 is pivotally positioned at a 45 pin or pivot 64 with head 65, between this head 65 and a blade or helical spring 66 with respective movability in such a way, that it may have also a position inclined to the pivot 64, as seen in Fig. 12. In the normal vertical position (ready for action) according to Fig. 9 the 50 hook-shaped holding piece 61 is supported against a stop 55 67 and is pressed by a blade spring 68 against this stop 67 and removed to this position after each motion.

When pushing the push-button 75 down against the action of the spring 54, the lateral nose 60 of the locking-plate 70 slides along the downwardly inclined transverse 60 part 62 of the hook-shaped holding-piece 61 by rotating the holding piece 61 on pivot 64 and is placed behind the transverse piece 62, shown in Figs. 11 and 14. Thus the locking plate 70 penetrates into the end slit 44 of the rotatable internal control element 26 and the latter is locked against rotating movement. When the push-button 75 is pushed again, the lateral nose 60 of the locking-plate 70 slides by further rotating of the holding piece 61 behind the downwardly inclined plate 63 of the holding piece 61 (Fig. 15) and slides along this plate 63 ahead of its initial position. In this manner the locking plate 70 moves again to its initial releasing position according to Figs. 9 and 13. The hook-shaped holding piece 61 thereby is instantly displaced in a position somewhat inclined to the locking plate 70 as seen in Fig. 12,

so that the nose 60 and the plate-like locking member 70 are moved by the spring 54 in the upward direction.

I claim:

1. A safety latch-bolt lock comprising a latch-bolt guided in a casing, a non-rotatable, axially movable hollow latch-pin traversing said latch-bolt for moving the latter from its locking position, and projecting on both sides of said lock casing with outer projecting parts, and handles on its outer ends, one of which is rotatably mounted, a locking member for the latch-bolt in the latch-pin, a rotatable internal control element for said locking member, one end of said latch-pin and the adjacent end of said rotatable internal control element having transverse slits, and an oppositely disposed and solely axially movable plate-like locking member in one of said handles for securing said rotatable internal control element against rotation, when said plate-like locking member is advanced in axial direction and extends in said transverse slits of said internal control element and said non-rotatable latch-pin.

2. A safety latch-bolt lock as per claim 1, in which a movable supporting and guiding member for said plate-like locking-member, an elastic element for yieldingly holding said plate-like locking member and said supporting member in the releasing position, and a movable driving means for the latter are disposed in said handle containing the plate-like locking member, said driving means projecting outwardly from said handle for moving said plate-like locking member in its locking position with respect to said internal control element.

3. A safety latch-bolt lock as per claim 1, in which a movable supporting and guiding member for said plate-like locking member, an elastic element for yieldingly holding said plate-like locking member and said supporting member in the releasing position and a movable driving means for the latter are disposed in said handle containing the plate-like locking member, said driving means projecting outwardly from said handle for moving said plate-like locking member in its locking position with respect to said internal control element, said supporting and guiding member and said driving means having on opposite sides inclined front-areas cooperating with each other for moving said non-rotating plate-like locking member in its locking position when said driving means is rotated.

4. A safety latch-bolt lock as per claim 1, in which a movable supporting and guiding member for said plate-like locking member, an elastic element for yieldingly holding said plate-like locking member and said supporting member in the releasing position, a movable driving means for the latter and an arrestation means for holding said plate-like locking member in its locking position are disposed in said handle containing the plate-like locking member, said driving means projecting outwardly from said handle for moving said plate-like locking member in its locking position with respect to said internal control element.

5. A safety latch-bolt lock as per claim 1, in which are disposed in said handle containing the plate-like locking member, a movable supporting member for said plate-like locking member, an elastic supporting element for yieldingly holding said plate-like locking member and said supporting member in the releasing position, a movable driving means for the latter, including a spring actuated push-button, a movement transmitting means be-

tween said push-button and said plate-like locking member, consisting of a yielding coupling plate rigidly connected at one end with said push-button, a movable supporting and control member transversely slidably mounted on said supporting member for the plate-like locking member opposite to the free end of said yielding coupling plate and cooperating therewith, a hook-shaped spring actuated arresting lever for arresting said plate-like locking member in its locking position being influenced by said transversely slidable control member.

5 10 15 20 25 30 35 40 45 50 55

6. A safety latch-bolt lock as per claim 1, comprising a movable supporting and driving means for said plate-like locking member including a spring actuated axially movable push-button rigidly connected with said plate-like locking member, a laterally projecting tap, attached to the latter, a hook-shaped spring actuated arresting lever for said plate-like locking member, pivotally attached to said hollow latch-pin in the range of said lateral tap and cooperating therewith for arresting said plate-like locking member in its locking position.

7. A safety latch-bolt lock as per claim 1, comprising a movable supporting and driving means for said plate-like locking member consisting of a spring actuated axially movable push-button rigidly connected with said plate-like locking member, a laterally projecting tap, attached to the latter, a hook-shaped spring actuated arresting lever for said plate-like locking member pivotally attached to said hollow latch-pin in the range of said lateral tap, means for yieldingly holding said hook-shaped holding lever in a position parallel to said plate-like locking member, an upper downwardly inclined transverse part and at the underside of the latter a laterally downwardly inclined sliding plate for said lateral tap of the plate-like locking member at said holding lever.

8. In a safety latch-bolt lock as per claim 1, in which are disposed in said handle containing the plate-like locking member, a movable supporting member for said plate-like locking member, an elastic element for yieldingly holding said plate-like locking member and said supporting member in the releasing position, a movable driving means for the latter, including a spring actuated push-button, a movement transmitting means between said push-button and said plate-like locking member, consisting of a yielding coupling plate rigidly connected at one end with said push-button, a movable supporting and control member transversely slidably mounted on said supporting member for the plate-like locking member opposite to the free end of said yielding coupling plate and cooperating therewith, a hook-shaped spring actuated arresting lever for arresting said plate-like locking member in its locking position being influenced by said transversely slidable control member and stop means for the plate-like locking member in its end position of axial movement preventing at the same time rotating of the locking member in the handle.
